(57) **CLAIM**

We claim the ornamental design for a child and cargo carrier, as shown and described.

DESCRIPTION

FIG. 1 is a top front perspective view of the child and cargo carrier, shown in its environment of use, according to the new design.

FIG. 2 is a top front perspective view of the child and cargo carrier shown in FIG. 1.

FIG. 3 is a bottom rear perspective view of the child and cargo carrier shown in FIG. 1.

FIG. 4 is a right side elevation view of the child and cargo carrier shown in FIG. 1.

FIG. 5 is a left side elevation view of the child and cargo carrier shown in FIG. 1.

FIG. 6 is a rear elevation view of the child and cargo carrier shown in FIG. 1.

FIG. 7 is a front elevation view of the child and cargo carrier shown in FIG. 1.

FIG. 8 is a top plan view of the child and cargo carrier shown in FIG. 1; and,

FIG. 9 is a bottom plan view of the child and cargo carrier shown in FIG. 1.

The broken lines in the drawings illustrate portions of the child and cargo carrier that form no part of the claimed design.

1 Claim, 6 Drawing Sheets
